UNITED STATES PATENT OFFICE

CHARLES H. ROHRIG, OF OELWEIN, IOWA

BANK PROTECTION DEVICE

Application filed March 2, 1931. Serial No. 519,490.

The object of my invention is to provide a bank protection device which is simple, durable and comparatively inexpensive to manufacture.

5 Further, it is my object to provide a bank protection device for cashiers' and tellers' windows and cages in which shield plates are normally latched in inconspicuous positions and are constrained toward movement to 10 positions directly above the counter of the cage to which positions they quickly and automatically move when the latch means is released.

15 More particularly, it is my object to provide lowerable shield plates above each cashier's or teller's window and raisable shield plates below the counters thereof with a latch mechanism to retain the shield plates in such positions and being releasable manually, 20 pneumatically, electromagnetically or in some similar manner.

25 A further object is to provide a rock shaft with latches on it for coaction with each shield plate to retain it in normal position whereupon the rock shaft, when rocked by manipulation of a control device in any cage, will release all the shield plates connected with the protection system to guard against 30 shots fired from the guns of bandits and hold-up men.

35 With these and other objects in view my invention consists in the construction, arrangement and combination of the various parts of my device, whereby the objects contemplated are attained, as hereinafter more fully set forth, pointed out in my claims, and illustrated in the accompanying drawings, in which:

40 Figure 1 is an inside elevation of two cashiers' or tellers' cages showing a partition between them in section and illustrating my bank protection device applied to the cages and in normal position.

45 Figure 2 is a similar view showing the shield plates in released or shielding position.

50 Figure 3 is an enlarged vertical sectional view on the line 3—3 of Figure 1 showing the latch for the raisable shield plate.

Figure 4 is a horizontal sectional view on the line 4—4 of Figure 1.

Figure 5 is a sectional view on the line 5—5 of Figure 1 showing the latch for the 55 lowerable shield plate.

Figure 6 is a view of a pneumatically operated system for releasing the shield plates.

Figure 7 is a detailed sectional view on the line 7—7 of Figure 6; and

Figure 8 is a semi-diagrammatic view 60 showing an electrically operated latch release.

On the accompanying drawings, I have used the reference numeral 10 to indicate a floor line and the numeral 12 to indicate a 65 ceiling line. A partition is shown at 14 between two tellers' or cashiers' cages and a counter is indicated at 16. Window openings 18 are provided above the counter in each teller's compartment. Ordinarily 70 drawers 20 are slidably mounted below the counters 16.

The purpose of my invention is to provide a shield plate type of protection for tellers' 75 and cashiers' compartments in banks and for any compartment in which valuables are kept and which are therefore subject to attack from holdup men. Specifically, my invention includes lowerable shield plates 22 above the window openings 18 and raisable 80 shield plates 24 between the window openings and mounted below the counter 16.

Guides 26 are provided for the shield plates 22 and guides 28 are provided for the shield plates 24. These guides are of any desired grooved type, such as shown in Figure 4 and the shield plates are preferably provided with rollers 30 which roll in the guides to reduce friction in the operation of 85 the shield plates.

The shield plates 22 and 24 are made of sheet metal of substantial weight to resist bullets from revolvers and other firearms. The lowerable shield plates 22, of course, 95 drop by gravity and may be assisted by additional weights 32 if desired or by springs. Each weight 32 is hung on a U-shaped bar 34, the ends of which are connected with a cross bar 36. Rods 38 extend upwardly from the 100 bar 36.

cross bar 36 and connect with the lower ends of the shield plates 22.

The rods 38 extend through openings 40 in the counter 16.

6 The shield plates 24 are constrained toward raised position by means of springs 42, each having an end connected with an eye 44 on a shield plate 24 and its other end connected with a stationary eye 46 on the under-
10 surface of the counter 16. The shield plates 24 are latched in lowered position by latch lugs 48 connected with a rock shaft 50. The latch lugs 48 coact with rollers 52 journaled on the shield plates 24.

15 The rock shaft 50 is supported in suitable bearings 54 on the undersurface of the counter 16. The rock shaft 50 may be rocked by a manually operated handle 56 connected by a link 58 with the rock shaft. Downward
20 pressure on the handle 56 will swing the latch lugs 48 in the direction of the arrow 60 (see Figure 3) so that the shield plates 24 will be raised by the springs 42. The counter 16 is provided with a slot 62 through which the
25 shield plates 24 may be extended to the position shown in Figure 2 by the springs 42 when the latches 48 are released.

The shield plates 22 are latched in raised position by latch hooks 64 also mounted on
30 the rock shaft 50 and best shown in Figure 5 of the drawings. The latch hooks 64 engage under rollers 66 mounted on the cross bars 36 of the rods 38.

35 *Practical operation*

In the operation of my bank protection device as thus far described, the handle 56 in any one of the cashiers' or tellers' cages (there usually being provided a considerable
40 number of them side by side) may be pushed downwardly for rocking the rock shaft 50 and thereby releasing all the latches 48 and the latch hooks 64. As a result of such unlatching, the shield plates 22 are lowered by
45 gravity and the shield plates 24 are raised by the springs 42.

Then they assume the position shown in Figure 2 to act as a complete shield across the front of the entire system of cages and in such position are effective against gun-fire.

50 Instead of the lever 56, push buttons in the floor may be operatively connected with the rock shaft 50 for rocking it when such push buttons are pushed by the foot of any one of the tellers or cashiers. As an alternative means of operating the latches a pneumatic system, as shown in Figures 6 and 7, may be provided. This may consist of a lever 68 on the rock shaft 50 constrained by
55 a spring 70 toward unlatched position and held by fluid pressure in a latched position. I have shown a diaphragm 72 acting on a push rod 74 for retaining the lever 68 in latched position. The diaphragm 72 is held
60 in such position by fluid pressure, such as

compressed air or gas or liquid under pressure.

Such fluid pressure may be supplied from a tank 76 into which it may be originally introduced through a fitting 78. By means of a control valve 80, the pressure in the pipe line 82 may be regulated as desired, regardless of the pressure in the tank 76. For instance, eighty or ninety pounds pressure might be introduced into the tank 76, but only fifteen or twenty pounds pressure maintained in the pipe line 82 by opening the valve 80 until the pressure reaches such valve and then closing it.

70 The pipe line 82 is in this manner charged with fluid pressure for maintaining the parts in the position shown in Figure 7. By means of release valves 84 which would release compressed air to atmosphere or fluid to a sewer, for instance, the rock shaft 50 may be rocked by the spring 70 whenever any of the valves 84 are open.

75 As shown in Figure 8, the rock shaft 50 may be retained in latched position by a spring 86. It may be moved to unlatched position by a solenoid 88 electromagnetically operating upon a plunger or armature 90. Current is supplied to the solenoid 88 whenever it is desired to lower and raise the shield plates 22 and 24 respectively and such current is controlled by push buttons 92 or other suitable manually operated or automatically operated switches. It will be obvious that
80 instead of manual operation, automatic operation from a burglar alarm could be used.

85 Different latch means and various types of actuating mechanism for the latch means can be used and various other changes may be made without departing from the real spirit and purpose of my invention. It is therefore
90 my intention to cover in my appended claims all mechanically equivalent structures and the like which can be reasonably included within their scope.

95 I claim as my invention:

1. For use with a counter, successive shield plates therealong, some of said shield plates being arranged therebelow and some being spaced thereabove, said shield plates being
100 raisable and lowerable respectively from initial positions and constrained from their initial positions toward positions immediately above said counter, means for latching said shield plates in their initial positions comprising a rock shaft extending along said counter and positioned therebelow, latch lugs and latch hooks on said rock shaft having lower surfaces to engage said raisable shield plates and upper surfaces to engage
105 said lowerable shield plates whereby said plates tend to balance each other relative to said rock shaft and manually controlled means for rocking said rock shaft to disengage said latch lugs and latch hooks from
110 said raisable and lowerable shield plates.

2. For use with a counter, successive shield plates therealong, some of said shield plates being arranged therebelow and some being spaced thereabove, said shield plates being
 5 raisable and lowerable respectively from initial positions and constrained from their initial positions toward positions immediately above said counter, means for latching said shield plates in their initial positions
 10 comprising a rock shaft extending along said counter and positioned therebelow, a roller on each plate, latch lugs and latch hooks on said rock shaft having lower surfaces engaging said rollers on said raisable shield
 15 plates and upper surfaces engaging said rollers on said lowerable shield plates whereby said shield plates tend to balance each other relative to said rock shaft and manually controlled means for rocking said rock shaft to disengage said latch lugs and latch hooks from said rollers to thereby release said shield plates.
3. For use with a counter, a shield plate spaced thereabove, rods extending from said shield plate and through said counter, a cross bar connecting said rods together on the side of said counter opposite said shield plate, means connected with said rods to constrain said shield plate toward said counter, means for latching said shield plate in position spaced from said counter comprising a rock shaft, a latch hook thereon engaging said cross bar and manually controlled means for rocking said rock shaft to disengage said latch hook from said cross bar.

Des Moines, Iowa, February 18, 1931.

CHARLES H. ROHRIG.
